UNITED STATES PATENT OFFICE

134,062

DESIGN FOR A DRESSER

Delwin C. Witman, Mansfield, Ohio, assignor to Sun Glow Industries, Inc., Mansfield, Ohio, a corporation of Ohio

Application July 15, 1942, Serial No. 107,544

Term of patent 3½ years

To all whom it may concern:

Be it known that I, Delwin C. Witman, a citizen of the United States, residing in Mansfield, in the county of Richland and State of Ohio, have invented a new, original, and ornamental Design for a Dresser, of which the following is a specification, reference being had to the accompanying drawing, forming part thereof, in which the figure is a perspective view of the dresser, showing my new design.

I claim:

The ornamental design for a dresser, as shown.

DELWIN C. WITMAN.
